(57) CLAIM

The ornamental design for a helmet, as shown and described.

DESCRIPTION

FIG. 1 is a front and side perspective view of a helmet, showing my new design;

FIG. 2 is a front elevational view thereof;

FIG. 3 is a side elevational view thereof, the side opposite being the mirror image thereof;

FIG. 4 is a top plan view thereof; and,

FIG. 5 is a bottom plan view thereof.

The rear portion of the article not shown in the drawing or described in the specification forms no part of the claimed design.
